SCREEN HOLDING STRIP SECURING MEANS

Albert Lang, Oakland, Calif.

Application April 17, 1950, Serial No. 156,353

2 Claims. (Cl. 160—327)

1

This invention relates to a screen holding strip securing means and is particularly concerned with means of securing the screen strip of a frameless window screen.

Screens of the character herein referred to are characterized by the provision of a screen holding strip, usually metallic, which extends throughout the length of at least one edge of the screen. The screens are secured to such strips in any conventional manner, frequently by inserting the screen edge within a return bent portion of the screen strip. The holding strip usually extends substantially beyond the edge of the screen to be engaged by securing means and in many instances the outward extension also acts as, or supports, a sealing member. Such holding strips have been secured to the window frame in various manners, the most simple being a simple flat securing plate formed integrally with the strip and screwed to the frame. In such securing construction the plates are frequently engaged by a single securing screw. In the operation of these devices, when tension is applied to the screen, a pivotal movement of the plate with respect to the screw occurs. Such pivotal movement not only releases the tension which is attempted to be applied but also the arrangement is frequently such that, upon such pivotal movement, the sealing engagement of the strip with the frame is destroyed. In certain arrangements of frameless screens tensioning means is provided in conjunction with the securingment of one screen edge while the opposite screen edge is secured by the simple plates and securing screws of the type above referred to. In such instances the tensioning means is frequently such as to provide only a given amount of tensioning movement and the original adjustment of the screen, in order to provide such tension, is provided by an adjustment of the securing screws which holds the plates. Obviously in such an arrangement the plate is free to move on the shank of the screw which secured it and since the head of the screw is spaced from the frame in order to permit such original adjustment the pivotal movement is excessive.

It is, therefore, among the prime objects of the present invention to provide a novel, simple and improved securing means for screen holding strips.

More specifically, it is among the objects of the present invention to provide a securing means for a screen holding strip which will preclude pivotal movement of such securing means in response to

2

the application of tension by the screen to the strip.

A further object of the present invention is to provide a novel and simple improved securing means for a screen holding strip which may be readily adjusted to vary the location of the strip and screen with respect to a window frame.

A further object of the present invention is to provide a securing means for a screen strip by which a single attaching screw is engaged by the securing means at a plurality of spaced points whereby tilting, canting or angular movement of the securing means with respect to the screw is precluded.

Another object of the present invention is to provide readily releasable securing means for a screen holding strip so that the strip and screen may be released from the attaching screw with a minimum of difficulty and without removing the securing elements from the strip.

Numerous other objects and features of the present invention will be apparent from consideration of the following specification taken in conjunction with the accompanying drawings, in which:

Fig. 1 is a front elevation of a screen strip detachably secured to a frame by securing means formed in accordance with the present invention.

Fig. 2 is a perspective view of one of the securing elements disclosed in Fig. 1.

Fig. 3 is a perspective view of another of the securing elements illustrated in Fig. 1.

Figs. 4, 5, 6 and 7 are vertical sectional views illustrating modified forms of securing element formed in accordance with the present invention.

Fig. 8 is a sectional view taken on the lines 8—8 of Fig. 7.

In general terms the securing means of the present invention may be defined as being characterized by a securing device adapted to be retained by an attaching screw which so engages the device as to preclude a tilting movement thereof with respect to the shank of the screw

securing means. In those forms of the invention shown in Figs. 1, 2, 3, 7 and 8 the securing means is releasable with respect to its attaching screw so that it may be permanently engaged with the strip and detached from the attaching screw and moved with the screen holding strip. In those forms of the invention illustrated in Figs. 4 and

5 the securing means is shown as readily detachable from the holding strip so that it may be permanently secured in adjusted position on the frame while the strip and screen are de-

tached from it. In Fig. 6 the securing means is not readily detachable from either the strip or the attaching screw. Release of the screw in such instance is by removal of the attaching screw from the frame. It is to be specifically understood, however, that these characteristics are interchangeable. For instance, the securing means of Figs. 1 to 3 may be detachable from the screen as in Figs. 4 and 5, while the devices of Figs. 4 and 5 may be more permanently secured to the strip and so forth. In Figs. 1 to 4 and 6 the securing means are shown as including a pair of spaced side members of a U-shaped bracket, such members having aligned apertures as terminal portions of bayonet slots for engaging the shank of the attaching screw at spaced points so that by such engagement of the screw shank pivotal movement with respect to the shank is precluded. In that form of the invention shown in Fig. 5 the pivotal movement is likewise precluded by the use of an elongated screw shank engaging portion, and in that form of the invention shown in Figs. 7 and 8 the plate is engaged by the extended surface of a bushing carried by the screw whereby the extended contact between plate and bushing is such as to preclude pivotal movement. Throughout the foregoing discussion and the following specification and claims the term "attaching screw" is used in a generic sense referring to any equivalent means secured to the window frame and engageable with the securing means.

Referring now more particularly to the drawings, the numeral 10 designates the screen which is of foraminous, flexible material usually such as woven wire, plastic or textile threads. At the edge of the screen 10 there is provided the screen holding strip 11 with which the screen may be attached in any conventional fashion. In those forms of the invention here shown, by way of illustration, the securement of the screen is by an enfoldment of the edge within a turned bent portion 12 of the strip 11. Above the return bent portion 12 of the strip 11 the strip is inwardly turned, as indicated at 13, and from the in-turned portion 13 a sealing flange 14 extends upwardly to engage a face of the window frame. For securing the strip to the window frame slots 15 are provided at spaced intervals along the strip and such apertures are adapted to receive therethrough engaging tongues 16 formed as integral extensions of the securing means. As hereinbefore referred to, in those forms of the invention shown in Figs. 1, 2, 3, 7 and 8 the tongue 16 is formed to lie parallel, thus permanently attaching the securing means to the strip and urging the flange 14 in sealing relation to the face of the frame, and in contact with the outer face of the flange 14. In Figs. 4 and 5, however, tongues 16 are turned angularly with respect to the flange 14 so that the strip may be disengaged from the tongue by pivotal sliding movement upwardly and outwardly from the tongue. If desired the tongues may be bent from the parallel position of Figs. 1, 2, 3 and 8 to assure the releasable position of Figs. 4 and 5 for assembly purposes and thereafter bent to the parallel position to lock them in position. Thereafter they may be released by bending outwardly to permit detachment of the strip from the securing means.

Referring more particularly to Figs. 1, 2 and 3, the securing means there shown are releasably engaged with their attaching screws so that the retaining means may be disengaged from the

screws and moved with the screen strip to which they are here shown as permanently engaged. Throughout the present disclosure the strip 11 is shown as a top holding strip. It will be understood, however, that the securing means is not limited to this application and it may be used for side or bottom holding strips if desired. In Fig. 1 the strip is shown as secured by spaced securing means, all of which are releasable from their attaching screws. For purposes hereinafter referred to it is found preferable to utilize end securing means of different structure from that of the central securing means. It will be understood, however, that such means is interchangeable and may be of one form or the other as desired.

As shown in Fig. 2, the end securing means generally indicated by numeral 17 have their tongues 16 mounted in the slots 15 which, in this instance, is elongated so as to permit the members 17 to slide with respect to the strip 11. Each member 17 comprises a body portion from which the tongue 16 extends having spaced parallel top and bottom members 18 joined by an intermediate front wall 19, the body being thus substantially U shaped in cross-section.

The body of the member 17 is provided with a bayonet type slot 20 extending through the front wall 19 inwardly and thereafter turning longitudinally of the body. The attaching screw, indicated at 21, is mounted in the frame to extend inwardly therefrom and on an axis parallel to the plane of the window opening. It will be readily understood that by sliding the member 17 with respect to the strip 11, the outwardly opening leg of the slot 20 may be caused to register with the screw 21 so as to permit the screw shank to enter the slot. Thereafter reverse sliding movement will locate the shank within the longitudinal leg of the slot to lock the securing means against transverse movement with respect to the shank of the screw. Subsequent release may of course be achieved by a reverse sliding of the member 17 with respect to the strip.

From the foregoing it will be seen that with the securing means 17 moved to the locked engaging position of Fig. 2 the shank of the attaching screw 21 is engaged on three sides by both the upper and lower side members 18 of the body. It will, of course, be readily seen that such engagement of the shank of the screw 21 at spaced points by relatively rigidly joined spaced elements of the retaining means will preclude any pivotal wobbling or canting movement of the retaining means body, and thus its tongue 16 with respect to the screw shank. Thus with the screw shank disposed on an axis parallel with the face of the frame the retainer and its tongue 16 will be secured at all times similarly parallel and the strip flange 14 will be caused to squarely seal against the face regardless of the tension applied and regardless of the vertically adjusted position of the securing means. It should further be noted that since the sustaining contact between the strip and retainer is at the slot 15 parallelism of the full extent of the tongue 16 with the flange 14 is not required to ensure a square relation of the flange with the face of the frame. Since tilting movement of the retainer is precluded, no tilting movement of the strip will result from the application of tension thereto. It will also be noted that, in addition to the above, the free edge of the lower wall 18 (see Fig. 3) bears against the screen which lies

over the inner flange of the return bent portion, thus cooperating with the tongue 16 in precluding pivotal movement of the strip with respect to the securing means.

The central securing means 22 shown in Figs. 1 and 3 comprises a body portion similar to that of Fig. 2 from which the tongue 16 extends in like manner, and similarly the top and bottom members 23 of the U-shaped body being joined by a front wall 24. Instead of the bayonet type of slot provided for the securing element 17, the central securing element 22 is provided with a single straight slot indicated at 25. Within the body there is provided a transversely slidable keeper 26 having a bayonet type slot indicated at 27. The keeper is slidably retained with the member 22 by suitable means such as a groove 28 formed in the upper face thereof which receives depressed detents 29 formed in the top member 23 of the body.

In the operation of this form of retaining means, it will be readily seen that when the retaining member is to be secured to the attaching screw 21, the keeper 26 is moved within the member 22 to cause the outer opening portion of the bayonet slot 27 to register with the slot 25, at which time both slots will be in position to receive the screw 21. For securing the member 22 against accidental displacement from the screw 21, the keeper is moved to the position indicated in Fig. 3 in which the longitudinal portion of the bayonet slot 27 receives the screw 21 while the outer wall indicated at 30 adjacent the longitudinal portion of the bayonet slot covers the opening 25 in the body of the member 22, thus precluding displacement of the retaining member from the screw. Since accidental sliding of the members 17 may take place, it is preferable to provide in conjunction therewith at least one retainer, such as shown in Fig. 3, in which accidental detachment from the screw 21 is precluded.

As referred to with respect to the retainer 17, it will be noted that the body portion of the retainer 22 is also formed by parallel upper and lower leg members which receive therethrough the shank of the retaining screw and which engage the retaining screw at spaced points. By such spaced engagement of the retaining member with the screw, it will be seen that a tilting or canting action of the retaining member with respect to the screw is precluded, and thus, despite the application of tension to the screen, strip or retaining member, there can be no tilting action and thus the relation of the retaining member and strip to the frame is permanently maintained in such manner as to preclude a loose and wobbling connection.

Referring now to Fig. 4 of the drawings, the securing member shown therein is substantially like the securing member of Fig. 2. In that form of the invention shown in Fig. 4, however, the retaining member is designed for permanent securement to the frame and thus, instead of a bayonet slot for receiving the securing screw 21, the upper and lower walls 31 and 32, respectively, of the body of the retaining member are simply apertured as indicated at 33 to receive the shank of the screw 21. Obviously, in such a structure the slot 15 which receives the tongue 16 is of no greater width than the tongue since there is no necessity for a sliding movement of the retaining member with respect to the strip.

While this form of the invention provides for a permanent connection of the securing means

to the frame, detachment of the securing means is permitted only by removal of the retaining screw. However, detachment of the strip from the securing means may be permitted by the outward inclination of the tongue 16 outwardly at an angle with respect to the flange 14 so that the screen may be removed by sliding the strip upwardly on the tongue 16. It will be understood, as hereinbefore mentioned, that the tongue may, if desired, be bent after receiving the strip to the parallel position indicated in Figs. 2 and 3.

In that form of the invention shown in Fig. 5, wobbling or pivotal movement of the retaining member with respect to the retaining screw 21 is precluded by forming the body of the retaining member as a cylindrical boss 34 through which the shank of the attaching screw 21 passes, the boss being extended right-angularly from a base portion 35 upon which the tongue 16 is formed. Obviously, since the boss 34 has an elongated bearing on the shank of the screw 21, pivotal movement thereof with respect to the shank will be precluded, it being, of course, understood that the bore of the boss snugly fits the shank of the screw. In this form of the invention also, since the retaining member is not removable from the attaching screw, the tongue 16 is shown as inclined to permit removal of the strip.

A further modification of the invention is disclosed in Fig. 6, in which the strip 11 is provided with an inwardly extending flange 36 having an inner terminal return bent edge 37 which is adapted to slidably receive a U-shaped retaining member 38, the upper face 39 of which is formed with extending ears 40 adapted to be received within the return bent portion 31 of the strip and to be retained thereby. The lower wall 41 of the retaining member is apertured in registry with an aperture of the upper face 39 and with a conforming aperture in the flange 36. Thus the attaching screw 21 is engaged by the retaining member 38 at spaced points in the manner of engagement of the retaining members of Figs. 2, 3 and 4, and thus by such spaced engagement the wobbling and tilting movement of the strip as well as the retaining member with respect to the screw is precluded.

Referring to Figs. 7 and 8, the retaining screw 21 is provided with a bushing 42 having a cylindrical body portion 43 and a screw head receiving portion 44 which snugly engages the head of the screw to preclude movement of the bushing with respect to the screw. The inner end of the body of the bushing 42 is turned inwardly, as indicated at 45, to snugly engage the screw at the inner edge, thus securely precluding any tilting movement of the bushing with respect to the shank of the screw. The inner face 46 of the inner end of the bushing is formed to provide an extended flat contact with the lower face 47 of the securing plate 48, the tongue 16 of which engages the strip in the manner which is shown in Figs. 1, 2 and 3. As more clearly indicated in Fig. 8, the slot 15 of the strip 11 which receives the tongue 16 is elongated as in the manner shown in Figs. 2 and 3, so as to permit sliding movement of the retaining plate 48. This form of the invention also provides a bayonet type slot 49, the arrangement being such that in this instance the retaining plate may slide with respect to the strip and with respect to the attaching screw 21 in a manner to releasably engage the retaining plate with the screw. As shown at 50, the plate may be provided with a right-angularly disposed finger

which is approximate to the outer head of the bushing when the plate is moved to screw engaging position and such proximity will assist in precluding pivotal or wobbling movement of the plate with respect to the screw. It will also be noted that the inner face of the head portion of the bushing is closely approximate the screen 10 itself, and at the point where the screen is supported by the inner face of the return bent portion 12 of the strip, such proximity also assisting in precluding a wobbling movement of the securing means with respect to the screw 21.

From the foregoing it will be seen that the present invention provides a novel and improved means by which a securing element is mounted with respect to a window frame in such manner as to preclude a wobbling, canting or angular movement of the securing means with respect to the frame or to the attaching screw which engages the frame. It will also be seen that the present invention provides means by which the securing device may be releasably retained on the securing screws in a manner precluding pivotal movement thereof with respect to the screw. The invention also provides a novel and improved means and further provides a manner of such engagement by which the securing means may slidably move with respect to the strip in order to facilitate engagement and disengagement thereof with the securing screw. The invention also provides means by which the strip may be releasably retained by securing means if desired.

In considering the foregoing, it will be understood that the invention is not limited to the structure, combination and inter-relation of parts here shown but that numerous changes, modification and the full use of equivalents may be resorted to in the practice of the invention as outlined in the appended claims.

Having thus described my invention, what I claim and desire to obtain by Letters Patent is:

1. A top screen edge holding assembly, adapted to be mounted on the upper end of a window frame, comprising a headed retainer adapted to be secured to the upper end of the window frame and extend downwardly from the downwardly facing surface of said upper end, a top holding strip supporting member slidably but non-tiltably mounted on the headed retainer and having a dimension in the direction of the length of the retainer less than the distance from the headed end of the retainer to the downwardly facing surface of the upper end of the window frame so as to be spaced from said surface, a top screen edge holding strip having its lower margin reversely bent for holding the upper end of a frameless window screen and having its upper portion formed with a flat face for sealing engagement with the outer face of the upper end of the window frame, said supporting member being connected to the top holding strip for holding it in a position for sealing engagement of said flat face with the men-

tioned outer face of the window frame, whereby the tension of the screen will pull the supporting member down against the head of the retainer and away from the downwardly facing surface of the window frame, but said supporting member will be prevented from tilting by its non-tiltable engagement with the retainer, said supporting member having an L-shaped slot formed therein to permit lateral removal thereof from the retainer.

2. A stop screen edge holding assembly, adapted to be mounted on the upper end of a window frame, comprising a headed retainer adapted to be secured to the upper end of the window frame and extend downwardly from the downwardly facing surface of said upper end, a top holding strip supporting member slidably but non-tiltably mounted on the headed retainer and having a dimension in the direction of the length of the retainer less than the distance from the headed end of the retainer to the downwardly facing surface of the upper end of the window frame so as to be spaced from said surface, a top screen edge holding strip having its lower margin reversely bent for holding the upper end of a frameless window screen and having its upper portion formed with a flat face for sealing engagement with the outer face of the upper end of the window frame, said supporting member being connected to the top holding strip for holding it in a position for sealing engagement of said flat face with the mentioned outer face of the window frame, whereby the tension of the screen will pull the supporting member down against the head of the retainer and away from the downwardly facing surface of the window frame, but said supporting member will be prevented from tilting by its non-tiltable engagement with the retainer, said supporting member comprising a reversely bent sheet metal element having aligned openings therein for the reception of the retainer, whereby engagement of the element at separated points with the retainer prevents tilting of the element relative to the retainer, said openings being in the form of L-shaped slots joined at the reverse bend to enable removal of the supporting member from the retainer.

ALBERT LANG.
